UNITED STATES PATENT OFFICE.

WILLIAM YELLOWLEY, OF KINGSTON, ONTARIO, CANADA.

DRIVING-BAND AND NOSING PRESS FOR PROJECTILES.

1,162,841.

Specification of Letters Patent.

Patented Dec. 7, 1915.

Application filed February 8, 1915. Serial No. 6,752.

To all whom it may concern:

Be it known that I, WILLIAM YELLOWLEY, a subject of the King of Great Britain, residing at No. 69 Union street, Kingston, 5 Province of Ontario, Canada, have invented certain new and useful Improvements in Driving-Band and Nosing Presses for Projectiles; and I do hereby declare that the following is a full, clear, and exact description 10 of the invention, such as will enable others skilled in the art to which it appertains to make and use the same.

The invention to be hereinafter described relates to driving band and nosing presses 15 for projectiles.

In order to more clearly disclose the construction, operation, and use of the invention, reference should be had to the accompanying drawings forming part of the present application.

Throughout the several figures of the drawings like reference characters designate the same parts.

In the drawings: Figure 1 is a top plan 25 view of the press; and Fig. 2 is a central, vertical section through the same.

The main objects of the invention are, to provide a compact, durable, and strong machine of simple construction and operation, 30 at relatively low cost, which can be used equally well for forming the noses of projectiles or for securing the driving bands on the same.

Referring to the drawings in detail, 1 35 designates the table which is supported by suitable legs 2 bolted thereto. This table is provided, on its upper face, with a number of, in this case six, integral, radial, bifurcated ribs or beams 3 the inner ends of 40 which unite to form an integral central hub 4. A reinforced casing 5 of approximately semielliptical shape is bolted to the hub and provided, in one side, with an opening of suitable size to permit the quick and easy 45 introduction of a projectile into the casing. A suitable nosing die 6 is removably secured in the top of casing 5, in alinement with the head of a plunger 7 vertically operative through a central bore in hub 4.

50 Plunger 7 is seated upon an extension ram 8 integral with the top of a hollow piston 9 operative in a cylinder 10 bolted to the under face of table 1. Ram 8 is operative in a socket 11 integral with the under face of 55 the table and acts to guide the piston in its vertical travel. The bottom of piston 9 is

also provided with an integral cylindrical extension 12 operative in a similar extension 13 of the cylinder 10. This insures accurate operation of the piston. The extension 60 12 is provided with four diametrically opposite L bores 14 extending from its lower end to a point near the top of the extension and being open at both ends, for a purpose to be later described.

65 A pipe 15 communicates with the lower end of the extension 13 of cylinder 10, at the center thereof, and is connected to a compressed air tank or other suitable source of supply of fluid pressure. A three-way cock 70 16 is interposed in this pipe and operated by a rod 17 and crank lever 18 so as to admit the compressed air, or the like into cylinder 10, or permit its escape therefrom.

75 The projectile, the nose of which is to be shaped, is properly heated and placed, nose up, on the head of plunger 7, the head of which is suitably recessed for this purpose. When the projectile is in position, the lever 18 is turned so as to admit the compressed 80 air beneath the extension 12 of piston 9. As the air enters the cylinder 10 it acts first on the relatively small surface of the extension 12 and raises the piston. As the piston is raised the air flows through bores 14 and 85 flows beneath the piston 9, so as to act on the entire lower face thereof and exert great pressure on the plunger 7. The advantage of this is that, the volume of air required to start the piston is small and the piston is 90 raised gradually and easily until the nose of the projectile is in the die, thus preventing any injurious sudden starts or jars. As piston 9 is raised the plunger 7 is forced upwardly and acts to force the nose of the 95 projectile firmly into the die 6, thus shaping it. This operation necessarily causes a certain flaking of the projectile, as it is shaped and cools, and for this reason a catch ring 19 is placed in the lower end of casing 5 100 to catch these flakings and prevent their falling into the mechanism of the press.

When the piston reaches the highest position for the proper forming of the nose of the projectile, the upper end of the stem 20 105 of an escape valve 21 seated in an opening in the bottom of the piston is brought into engagement with a set screw 22 threaded through the table 1. This forces valve 21 off of its seat so that the air beneath the piston 9 110 enters the same and escapes through ports 23 through the top thereof. As soon as this

happens the three-way valve 16 is opened to permit escape of the air beneath piston 9, the piston being returned by gravity to its initial position, and the projectile is removed and cooled. As the operative travel of piston 9 can be regulated by set screw 22, and as the die 6 and plunger 7 are easily interchangeable, it will be obvious that this machine can be quickly and easily adapted to shape projectiles of practically any size.

When it is desired to use the machine for securing the driving bands of projectiles, the catch ring 19 and the plunger 7 are removed. This is done by simply lifting the plunger into the casing 5 and removing it, and then removing the catch ring. The projectile, which is provided with the usual ring groove, with the driving band temporarily secured in position by suitable means, such as striking lightly with a hammer so as to force it slightly into the groove, is then placed in the upper part of the hub 4 of the table 1 the upper end of which is suitably bored for this purpose. In this position the lower portion of the projectile is between the inner ends of a plurality of radially disposed blocks 24 slidably mounted in suitable grooves in the hub 4, the inner faces of which are slightly concaved. The outer ends of these blocks are pivotally connected to the inner ends of toggle arms 25 pivotally connected at their outer ends to the inner ends of toggle arms 26 the outer ends of which are pivotally connected to lugs integral with blocks 27 secured about the inner face of the rim of table 1. This forms a plurality of simple toggle connections the centers of which are pivotally connected to the upper ends of arms 28 the lower ends of which are pivoted to lugs integral with the upper face of piston 9. When the piston is raised, as previously described, the toggles are straightened out by means of arms 28 and force the blocks 24 inwardly. The blocks engage the driving band and force it tightly into its groove. As soon as this has been accomplished, the three-way cock 16 is opened to permit escape of the air from beneath the piston which returns by gravity to its original position, after which the projectile is removed and the driving band is shaped and pressed in the usual manner.

In order to adapt the machine for projectiles of different diameters it is necessary that the upward movement of the piston be positively limited. As the travel of the piston is much less in pressing the driving bands than in nosing, it has been found desirable to provide separate means for effecting this result, though, if desired, the set screw 22, valve 21, and their coöperating parts, could be adapted to effect this result also. A plurality of radially disposed equally spaced limiting screws 29 are threaded through table 1, directly above integral

bosses 30 formed on the upper face of piston 9. When the piston has been raised so that the bosses engaging the limiting screws its upward movement is, of course, positively checked, thus avoiding damage by exerting too great a pressure on the driving band and projectile. As soon as the upward movement of the piston is stopped, the three-way cock 16 is opened and the piston is lowered, as described. By adjusting the limiting screws 29 the travel of the piston may be adjusted and, therefore, the travel of the blocks 24 may be regulated to suit projectiles of different diameters, as will be obvious.

A circular plate or cover 31 of suitable construction is secured on top of table 1 to protect the operating mechanism and to furnish a suitable top or surface on which the projectiles being operated upon may be placed so as to be readily accessible.

It is thought that the construction, operation, and use of the invention will be clear from the preceding detailed description.

Changes may be made in the construction, arrangement, and disposition of the several parts of the invention within the scope of the claims without in any way departing from the field and scope of the same, and it is meant to include all such within this application wherein only a preferred form has been disclosed.

Having thus fully described my invention, what I claim as new and desire to secure by Letters Patent is:

1. In a machine of the character described, a table provided with an integral central hub, a casing secured to the said hub, a die removably secured in the upper end thereof, a cylinder secured to the under face of said table, a piston operative therein, a plunger mounted thereon and operative in said casing, means for admitting fluid under pressure beneath said piston and for permitting escape of the said fluid from beneath the said piston, means for permitting the escape of the pressure fluid from beneath the piston when the piston has reached a predetermined point, radially disposed blocks slidably operative in the hub of the said table, means for forcing the said blocks inwardly as the piston rises and for withdrawing the said blocks as the piston falls, and means for positively limiting the upward travel of said piston.

2. In a machine of the character described; a table provided with an integral central hub centrally bored to receive a plunger; a casing secured to the upper face of the said hub and provided with an opening in one side; a nosing die removably secured in the upper end thereof; a cylinder secured to the under face of said table and provided with a cylindrical extension; a hollow piston operative in said cylinder and provided with a

bottom cylindrical extension operative in the cylindrical extension of the cylinder, the said extension of the piston being provided with radially disposed L bores; a removable plunger mounted on the top of the said piston and slidably operative through the said hub; a three way valve connected to the said extension of the said cylinder; a spring pressed valve adapted to normally close an opening 10 through the bottom of the said cylinder; means for unseating the said valve when the piston has reached a predetermined point; radially disposed blocks slidably operative

in the hub of the said table; toggle arms connected to said blocks and to the rim of 15 the table; arms connected to the said toggle arms and to the said piston; and means for positively limiting the upward travel of the said piston.

In witness whereof I have hereunto set 20 my hand in the presence of two witnesses.

WILLIAM YELLOWLEY.
